US00D948614S

(12) **United States Design Patent** (10) **Patent No.:** **US D948,614 S**
DeCarlo et al. (45) **Date of Patent:** **** Apr. 12, 2022**

(54) **FILE FOLDER**

(71) Applicant: **IdeaStream Consumer Products, LLC**, Cleveland, OH (US)

(72) Inventors: **Anthony J. DeCarlo**, Parma, OH (US); **Curtis Patrick Taylor**, Chagrin Falls, OH (US); **Chaneol Chung**, Hollywood, FL (US); **Daniel V. Perella**, Hudson, OH (US)

(73) Assignee: **IdeaStream Consumer Products, LLC**, Cleveland, OH (US)

(**) Term: **15 Years**

(21) Appl. No.: **29/710,992**

(22) Filed: **Oct. 28, 2019**

Related U.S. Application Data

(60) Continuation of application No. 29/621,758, filed on Oct. 11, 2017, now Pat. No. Des. 865,058, which is a continuation-in-part of application No. 29/564,534, filed on May 13, 2016, now Pat. No. Des. 837,295, which is a continuation of application No. 29/491,171, filed on May 19, 2014, now Pat. No. Des. 759,161, which is a continuation of application No. 29/464,580, filed on Aug. 19, 2013, now Pat. No. Des. 705,351, which is a continuation of application No. 29/415,798, filed on Mar. 14, 2012, now Pat. No. Des. 688,302, which is a continuation of application No. 29/368,350, filed on Aug. 23, 2010, now abandoned, which is a continuation of application No. 29/299,333, filed on Dec. 21, 2007, now Pat. No. Des. 622,320, said application No. 29/621,758 is a continuation-in-part of application No. 14/856,689, filed on Sep. 17, 2015, now abandoned, which is a continuation of application No. 14/064,626, filed on Oct. 28, 2013, now Pat. No. 9,156,303, which is a continuation of application No. 13/151,751, filed on Jun. 2, 2011, now Pat. No. 8,567,659, which is a division of application No. 12/035,079, filed on Feb. 21, 2008, now Pat. No. 7,954,694.

(57) **CLAIM**

The ornamental designs for a file folder, as shown and described.

DESCRIPTION

FIG. 1 is a top plan view of a first embodiment of a file folder showing the new design in an open position;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof shown in the closed position;

FIG. 8 is a top plan view thereof;

FIG. 9 is a bottom plan view thereof; and

FIG. 10 is an isometric view thereof.

FIG. 11 is a top plan view of a second embodiment of a file folder showing the new design in an open position;

FIG. 12 is a bottom plan view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof shown in the closed position;

FIG. 18 is a top plan view thereof;

FIG. 19 is a bottom plan view thereof; and

FIG. 20 is an isometric view thereof.

FIG. 21 is a top plan view of a third embodiment of a file folder showing the new design in an open position;

FIG. 22 is a bottom plan view thereof;

FIG. 23 is a front elevational view thereof;

FIG. 24 is a rear elevational view thereof;

FIG. 25 is a left side elevational view thereof;

FIG. 26 is a right side elevational view thereof;

FIG. 27 is a top plan view thereof shown in the closed position;

FIG. 28 is a top plan view thereof;

FIG. 29 is a bottom plan view thereof; and

FIG. 30 is an isometric view thereof.

FIG. 31 is a top plan view of a fourth embodiment of a file folder showing the new design in an open position;

FIG. 32 is a bottom plan view thereof;

FIG. 33 is a front elevational view thereof;

FIG. 34 is a rear elevational view thereof;

FIG. 35 is a left side elevational view thereof;

FIG. 36 is a right side elevational view thereof;

FIG. 37 is a top plan view thereof shown in the closed position;

FIG. 38 is a top plan view thereof;

FIG. 39 is a bottom plan view thereof; and,

FIG. 40 is an isometric view thereof.

The broken lines are included for the purpose of illustrating parts of the file folder that form no part of the claimed design.
